UNITED STATES PATENT OFFICE.

SIMEON C. LAWLOR, OF CHICAGO, ILLINOIS.

SIEVE.

1,136,243.

Specification of Letters Patent. Patented Apr. 20, 1915.

Application filed June 3, 1912. Serial No. 701,268.

To all whom it may concern:

Be it known that I, SIMEON C. LAWLOR, a citizen of the United States, residing at Chicago, in the county of Cook and State of Illinois, have invented certain new and useful Improvements in Sieves; and I do hereby declare the following to be a full, clear, and exact description of the invention, such as will enable others skilled in the art to 10 which it appertains to make and use the same.

This invention relates to improvements in sieves, and particularly to the type in which both the container and shaker handles are 15 adapted to be grasped in the same hand of the operator.

Among the objects in view are the effective, relative vibration of the container and shaker, the maintenance of the shaker in 20 proper position, and the simple, cheap and efficient construction of the shaker handle with its operating means.

With these and further objects in view as 25 will hereinafter in part be stated and in part become apparent, the invention comprises certain novel construction, combinations and arrangements of parts as herein set forth and claimed.

In the accompanying drawing,—Figure 1 30 is a perspective view of a sieve embodying the features of the present invention, a wall of the container being broken away for disclosing interior structure. Fig. 2 is a horizontal, transverse section taken on the plane 35 indicated by line 2—2 of Fig. 1, and looking downwardly. Fig. 3 is a view similar to Fig. 2 of a modified embodiment. Fig. 4 is a vertical section therethrough taken on the plane indicated by line 4—4 of Fig. 3.

Referring to the drawing, 1 indicates a 40 container which may be of the usual type and provided at its lower end with a screen 2. Arranged within the container immediately above the screen is a shaker 3. The 45 shaker 3 preferably consists of a single wire bent into convolutions forming a body terminating with the end portions of the wire juxtaposed and constituting an operating arm 4, which is extended through an aperture 5 in the wall of the container 1 for 50 enabling reciprocation of the shaker within the container. It is to be noted that the wire forming the shaker 3 is bent to extend in the general direction of reciprocation a 55 distance greater than the distance of re-

ciprocal movement of the shaker, and a cross rod 6 is fixed to the walls of the container 1 and extends above and across the shaker 3 in position for preventing upward displacement of the shaker.

The container 1 is provided with a handle 7 which is slotted at its lower portion, as at 8, and is preferably formed intermediate its length with transverse slots 9, 9. A shaker operating handle 10 is arranged within the 60 handle 7 and consists preferably of a transversely concavo-convex strip of spring material, a portion of the material extending beyond the handle portion and forming a spring 10' which is bent to extend downwardly through the slots 9 for sustaining the handle 10 in place. The lower portion of the handle 10 is folded or bent together to form an extension 10'' which projects 65 downwardly through the slot 8 and is pivotally connected to the operating arm 4, as by extending through an eye at the outer end of the arm.

It will be noted that in operation the handle 7 is engaged by the palm of the hand of the operator while his fingers are passed back of the handle 10, whereby both handles are grasped in the one hand of the operator. A contracting movement of the fingers will serve to draw the handle 10 toward the 80 handle 7 and thus draw the arm 4 outwardly, imparting movement to shaker 3 in one direction. When the limit of outward movement is reached by handle 10, the operator merely releases his grasp sufficiently to allow 85 the handle to move inwardly or toward the container 1, such movement being effected by the expanding pressure of the curved upper portion of spring 10'. This inward movement thus effects a return reciprocation of 90 the arm 4 and shaker 3. When the sieve is filled with flour or other substance to be sifted, the operator can easily reciprocate shaker 3 by repeating the operation stated, either rapidly or slowly, according to the 95 quantity of sifted material to be discharged from the screen.

In Figs. 3 and 4, I have illustrated a further embodiment of the present invention which is particularly well adapted for enabling effective relative movement of the shaker with respect to the container and of the container with respect to the shaker, each moving at the same time as the other in an opposite direction during operation.

In this structure the container 1' is provided with the screen 2', and shaker 3', which latter is formed with the outstanding end portions 4' which are bent together at their outer extreme and thus form an operating arm, which is pivotally engaged by an actuating handle 11, which handle extends upwardly from the arm and at its upper end is pivotally connected to the container 1'. By preference, each end portion of the wire constituting the operating arm is surrounded by a coiled spring 12, which has its inner end pressing against the container 1' and its outer end engaging or fixed to the bent outer portion of the respective rod, the springs 12 exerting an expanding pressure tending to hold the lower portion of handle 11 in its outermost position. A supporting handle 7' is fixed to the container 1' within the handle 11, so that the said supporting handle may be grasped, during operation, by the fingers of the operator while the palm of the hand engages the handle 11, and a contraction of the hand effects movement of the two handles toward each other, whereby the container 1' is drawn in one direction and the shaker 3' is reciprocated in the opposite direction, a reverse movement of the respective parts being effected by loosening of the grasp of the hand, allowing the handle 11 to swing outwardly under the pressure of spring 12. The confining rod 6' is employed in this construction to prevent the shaker 3' from being displaced, and the wire of which the shaker is formed is extended in the direction of reciprocation suff-

ficiently to insure against the shaker escaping from beneath the confining rod.

What I claim is:—

1. In a sieve, the combination with a container, and a screen, of a shaker disposed within the container, above the screen, and comprising bent wire, parallel portions of the wire being extended from the shaker through the wall of the container, and forming an operating arm for the shaker, and being disposed in spaced relation to prevent rocking of the arm, an operating handle for said arm outside of the container, and a handle for the container contiguous the first-mentioned handle and disposed for enabling the hand of the operator to grasp both handles. 40

2. In a sieve, the combination, with a container and a screen therein, of a shaker slid- 45 ingly disposed above the screen, and a handle outstanding from the container, arms extending from the shaker through the walls of the container at opposite sides of the handle, a second handle pivotally connected to the container at its upper portion and engaging said arms, and a spring pressing the last-mentioned handle outwardly, the two handles being disposed for being grasped by one hand of the operator. 50

In testimony whereof I affix my signature in presence of two witnesses.

SIMEON C. LAWLOR.
